UNITED STATES PATENT OFFICE.

WASHINGTON A. H. BOGARDUS, OF NEW YORK, N. Y.

TUBULAR DESPATCH APPARATUS.

SPECIFICATION forming part of Letters Patent No. 669,886, dated March 12, 1901.

Application filed July 10, 1900. Serial No. 23,087. (No model.)

To all whom it may concern:

Be it known that I, WASHINGTON A. H. BOGARDUS, a citizen of the United States, residing at "The Montana," One Hundred and Twenty-fourth street and Mount Morris avenue, in the city of New York, county of New York, and State of New York, have invented a new and useful Improvement in Tubular Despatch Apparatus, of which the following is a specification.

My invention relates to improvements in the general class of tubular transit systems in which fluid under pressure or suction is utilized as a motive force; and the present improvements relate particularly to apparatus for ascertaining the position of and moving carriers in such tubes without removing such pressure or suction therefrom; and it consists of sight-indicators and moving levers applied to such tubes at points where such ascertainment and movement is requisite.

This invention is particularly applicable to the tube adjacent switches, gates, valves, transmitters, receivers, and all points upon a tubular transit-line where carriers are likely to stick, jam, or block and where their position is required to be located and such carrier or carriers moved forward, backward, or away from such obstruction or point; and the production of a compact and convenient device to accomplish such ascertainment or movement constitutes the object of this invention. I attain this object by the mechanism illustrated in the accompanying drawings, in which—

Figure 1 is a side elevational view of a section of transit-pipe adjacent a gate with my invention applied thereto; Fig. 2, a horizontal section on line X-X of Fig. 1, showing my device normally at rest; and Fig. 3, a similar view showing my device in position for moving a carrier.

Similar numerals designate similar parts throughout the several views.

Referring to the drawings, 1 represents a section of transit-pipe; 2, a gate therein; 3, a chest forming part of said pipe; 4, a similar oppositely-disposed chest; 5, 6, plates of glass or other transparent material mounted in said chest; 7, a stuffing-box upon one end of chest 3; 8, a shaft mounted in said stuffing-box and

capable of rotary and longitudinal movement therein; 9, an arm integral with the inner end of said shaft; 10, a lever fixed to the outer end of said shaft, and 11 a carrier resting within the tube.

The operation is as follows: We will suppose that a carrier is jammed in the half-closed gate 2 and it is desired to withdraw said carrier from under the gate against the pressure to allow the gate to close. The position of the carrier is first ascertained by applying light, if the ordinary light is not sufficient, to the glass 6 in chest 4 and glancing through glass 5 in chest 3. When the exact position of the carrier is ascertained, the shaft 8 is drawn out or pushed in until the arm 9 is in such a position that when rotated it will engage a packing-ring, similar part, or end of the carrier. Then the shaft is rotated by hand-lever 10 until arm 9 engages the carrier and is pushed in or pulled out, as the case may require, carrying the carrier with it, the gate being previously raised to permit the carrier to clear the same.

When the shaft or levers are not in use, the weight of lever 10 carries the arm 9 into the chest 3 and out of the passage of the carriers.

It is obvious that various changes may be made in the details, construction, and application of this device without departing from the spirit of my invention.

Having now described my invention, what I claim, and desire to secure by Letters Patent, is—

1. In combination with a tubular transit-pipe, a carrier-moving mechanism, substantially as and for the purpose set forth.

2. In combination with a tubular transit-pipe, an enlarged portion thereof, a shaft journaled therein and capable of rotary and longitudinal movement, a lug upon one end of said shaft and means upon the other end for rotating and moving said shaft, substantially as described.

3. In combination with a tubular transit-pipe, an enlarged portion thereof, a stuffing-box therein, and a shaft journaled in said stuffing-box parallel to said transit-pipe and capable of rotary and longitudinal movement, a lug upon the inner end of said shaft adapted to enter said transit-pipe upon the rotation of

said shaft and means upon the opposite end of said shaft for moving and rotating the same, substantially as described.

4. In combination with a tubular transit-
5 pipe, a sight-indicator and a carrier-moving lever, substantially as and for the purpose set forth.

5. In combination with a tubular transit-
10 pipe, oppositely-disposed sight-indicators and
10 a carrier-moving lever capable of rotary and

longitudinal movement, substantially as and for the purpose set forth.

In testimony whereof I have signed my name to this specification in the presence of two subscribing witnesses,

WASHINGTON A. H. BOGARDUS.

Witnesses:

GEORGE E. PHELPS,

GEORGE G. POWELL.
